United States Patent Office

Des. 195,682

Patented July 16, 1963

195,682

TRAY OR THE LIKE

Merrill A. Grogel, Henrico County, Va., assignor to Reynolds Metals Company, Richmond, Va., a corporation of Delaware

Filed June 27, 1962, Ser. No. 70,701

Term of patent 14 years

(CL. D44—10)

I claim:

The ornamental design for a tray or the like, as shown.
